UNITED STATES PATENT OFFICE.

FRANCIS W. CARPENTER, OF HARRISON, NEW YORK.

TOY SLEIGH.

SPECIFICATION forming part of Letters Patent No. 267,778, dated November 21, 1882.

Application filed October 5, 1882. (No model.)

To all whom it may concern:

Be it known that I, FRANCIS W. CARPENTER, of Harrison, in the county of Westchester and State of New York, have invented an improvement in Toy Sleighs, of which the following is a specification.

In Letters Patent No. 227,956, reissued March 14, 1882, No. 10,063, toy cars are represented with the bodies of thin cast metal.

10 My present invention is an improvement on the foregoing toy; and it consists in a toy sleigh with a body having sides and back and a dash-board all cast in one piece, and a seat that is supported on cast-lugs and secured by 15 a rivet or screw. The runners are of cast metal riveted or fastened to the body, and the wheels on which the toy sleigh runs are connected between the runners and bearings cast upon the under side of the sleigh. The axis 20 of the wheels passes through the said runners and aids in supporting them. The shafts are fastened to the under side of the sleigh, and are provided with a cross-bar at the outer end, for strengthening the shafts and for receiving 25 an attaching-cord.

In the drawings, Figure 1 is a longitudinal sectional view of the sleigh. Fig. 2 is an inverted plan.

The sleigh-body is provided with the sides *b*, 30 curved back *c*, with curved upper edges, the dash-board *d*, and low front *e*, all cast in one piece. There are downwardly-projecting bearings *q* for the axis *f* that passes through said bearings *q* and through the wheels *g* and the 35 runners *h*.

The runners are each cast in imitation of sleigh-runners and provided with top flanges, *i*, by which the sleigh body and runners are fastened together by rivets or other suitable 40 means. The ends of the axis *f* passing through the runners aid in tying them together, so that they are strong, and there is a space between each runner and the adjacent bearings *q* for the reception of the wheel *g*.

45 The shafts *l* are cast with cross-piece *m* at the back and a bar, *n*, across between the front ends, in which is a hole for a cord or string, by which the toy can be drawn about. The rear ends of the shafts are below the front part 50 of the sleigh and riveted thereto at *k*. The rivets may be cast on the shafts.

The horse *o* is similar to that shown in my Patent No. 234,534, and the same is upon a cross-wire, *o*, that passes through the horse and also through the lugs *p* that project up 55 from the top of the shafts.

Below the shafts there is a hanging standard with a pivot-pin for the wheel *s* with a crank-pin, *t*, and connection to the horse's head, so as to give a rocking movement to the horse, 60 the same as in my Patent No. 241,188.

The seat *u* of the sleigh-body is cast to fit inside the back part, and there are lugs *v* cast on said sides and back for the seat to rest upon, and a rivet or screw, *w*, serves to hold the 65 same firmly in place.

This cast-metal vehicle-body may be placed on wheels instead of runners, and I remark that the bottom *a* of the vehicle-body is shown as a separate plate of metal secured to the 70 body by rivets; but it may be soldered or otherwise fastened in place, or it may be cast in one with the other parts of the body.

The parts may be made of malleable cast-iron, so that the pins that form the rivets may 75 be cast with the respective parts.

I claim as my invention—

1. A toy vehicle-body having its sides and dash-board formed of one piece of cast metal, substantially as specified. 80

2. In a toy sleigh, the combination of a cast-metal body and cast-metal sleigh-runners fastened to the body, substantially as set forth.

3. The combination of a toy sleigh having a cast-metal body with metal runners fastened 85 to the body, and an axle and a wheel or wheels, substantially as specified.

4. A cast-metal toy vehicle-body having its sides and back for seat formed of one piece of cast metal, substantially as set forth. 90

5. A toy vehicle-body having cast-metal sides with one or more lugs cast on the sides, in combination with a piece adapted to rest on the lug or lugs to form a seat.

6. A toy vehicle-body having cast-metal 95 sides and back, in combination with a metal bottom fastened to the body, substantially as set forth.

7. The combination, in a toy, of a cast-metal body, cast-metal shafts, and a bar connecting 100 the outer ends of the shafts, substantially as set forth.

8. The toy vehicle-body having sides and back for seat and a dash-board in one piece of cast metal, substantially as set forth.
9. The toy vehicle-body having sides, curved back, and low front ~~e~~ in one piece of cast metal, substantially as set forth.
10. The toy having a body and cast-metal runners with flanges at their upper edges and attaching-rivets, substantially as set forth.
11. The combination, in a toy sleigh, of a cast-metal body, cast-metal runners, wheels, and a shaft for said wheels passing through the runners, substantially as set forth.
12. In a toy, a cast-metal body in one piece,

having sides, rounded back and front, and downward projections, in combination with the axle passing through such downward projections and wheels upon such axle, substantially as set forth.

13. The toy vehicle - body having sides, curved back, and dash-board in one piece of cast metal, substantially as set forth.

Signed by me this 4th day of October, A. D. 1882.

FRANCIS W. CARPENTER.
